(57) **CLAIM**

The ornamental design for a solar power trailer, as shown and described.

DESCRIPTION

FIG. 1 is a top front perspective view of a solar power trailer, showing my design;

FIG. 2 is a top elevation view thereof;

FIG. 3 is a bottom elevation view thereof;

FIG. 4 is a left elevation view thereof;

FIG. 5 is a right elevation view thereof; and,

FIG. 6 is a front elevation view thereof, with a rear elevation view being a mirror image of the front elevation view.

The broken lines shown in the drawings depict portions of the solar power trailer that form no part of the claimed design.
